UNITED STATES PATENT OFFICE.

GEORGE V. STRAHAN, OF NEWARK, NEW JERSEY, ASSIGNOR TO MITCHELL VANCE CO., INC., OF NEW YORK, N. Y., A CORPORATION OF NEW YORK.

DESIGN FOR A CHANDELIER-BODY PLATE FOR A LIGHTING-FIXTURE.

56,775.

Specification for Design.

Patented Dec. 14, 1920.

Application filed June 30, 1920. Serial No. 393,174. Term of patent 7 years.

To all whom it may concern:

Be it known that I, GEORGE V. STRAHAN, a citizen of the United States of America, residing in the city of Newark, county of Essex, and State of New Jersey, have invented a new, original, and ornamental Design for a Chandelier-Body Plate for a Lighting-Fixture, of which the following is a specification, reference being had to the accompanying drawings, forming part thereof.

Figures 1 and 2 of the accompanying

drawings are respectively plan and cross-sectional views of a chandelier body plate for a lighting fixture, showing my new design. The surface ornamentation is shown only upon a portion of the plan view; it being understood that the surface ornamentation shown is repeated over the entire surface.

I claim:

The ornamental design for a chandelier body plate for a lighting fixture, as shown.

GEORGE V. STRAHAN.
